UNITED STATES PATENT OFFICE.

WEBSTER C. BALL, OF CLEVELAND, OHIO.

DESIGN FOR A HAND FOR TIMEPIECES.

SPECIFICATION forming part of Design No. 22,703, dated August 15, 1893.

Application filed April 26, 1893. Serial No. 471,983. Term of patent 14 years.

To all whom it may concern:

Be it known that I, WEBSTER C. BALL, a citizen of the United States, and a resident of Cleveland, county of Cuyahoga, and State of Ohio, have invented and produced a new and original Design for Hands for Timepieces, &c., of which the following is a specification, reference being had to the accompanying drawing, forming part thereof, and which represents a view of a hand embodying my design.

The leading feature of my design consists in an oval, open conformation, at about the end of the hand, the inner side of which conformation has approximately the shape of a crescent; and a round enlargement of a less diameter than such oval conformation and at the inner side of the same. The hand A, is

formed at about its end with an oval conformation, B,—transverse to the hand. The inner side b, of said conformation is substantially crescent-shaped. A round enlargement, C, of less diameter than the oval conformation, is formed upon the hand, inside of said conformation.

What I claim is—

The design for a hand for timepieces, &c., substantially as described and illustrated.

In testimony that I claim the foregoing to be my invention I have hereunto set my hand this 15th day of February, A. D. 1893.

WEBSTER C. BALL.
